CORNER PANTRY CABINET

Ronald D. Pearson, 12320 98th Ave. E.,
Puyallup, Wash. 98371

Filed Nov. 12, 1973, Ser. No. 415,287

Term of patent 14 years

Int. Cl. D6—04

U.S. Cl. D6—146

The figure is a front and top perspective view of a corner pantry cabinet showing my new design, the rear and sides being plain and unornamented.

I claim:

The ornamental design for a corner pantry cabinet, as shown and described.
